UNITED STATES PATENT OFFICE.

EDMUND S. DICKEY, OF BALTIMORE COUNTY, MARYLAND, ASSIGNOR TO AMERICAN METER COMPANY, INC., OF NEW YORK, N. Y., A CORPORATION OF DELAWARE.

GAS-METER.

1,306,217.

Specification of Letters Patent. Patented June 10, 1919.

Application filed March 20, 1918. Serial No. 223,574.

To all whom it may concern:

Be it known that I, EDMUND S. DICKEY, a citizen of the United States, residing in the county of Baltimore and State of Maryland, have invented certain new and useful Improvements in Gas-Meters, of which the following is a specification.

This invention relates to dry-type gas meters.

10 The object of the invention is to increase the capacity of the meter, without materially increasing the size of the unit, and at the same time, decrease the number of revolutions or cycles of the rotary and other moving parts, thus reducing the retarding effects of the meter mechanism upon the gas in passing through the meter, and greatly adding to the life of the meter, as well as the continued accuracy in measurement of 15 the gas, due to the absence of lost motion that, as above indicated, results from wear.

Another object of my invention is to so construct the gas channels that complete drainage of the gas condensates is accomplished.

In the installation of meters, size or dimensions of the units is a consideration of great importance, in connection with the utilization of floor space, and this particularly with regard to the width and height of the meter, the depth of the unit being of comparatively minor importance.

It is well recognized that in the average town or city, the greater portion of gas consumption will be found in the downtown section, where there is an ever increasing tendency toward greater consumption of gas for industrial purposes, and at the same time, it is usually found that in such sections, the distributing plants have their oldest mains, which are subject to the greatest leakage. With the natural tendency of the gas to throw its heavier pressure into what are usually the higher outlying sections of 40 the community, the result is that the lower sections, where the industrial requirements are greatest, suffer from lack of pressure.

To offset this loss, the distributing plant is compelled to increase the pressure in the downtown sections, with the undesired result of unnecessary increase in pressure in the outlying sections, and consequently, any means, device or contrivance that will facilitate the distribution of gas to industrial 50 and other consumers in all sections, and par-

ticularly in low sections, with a minimum amount of pressure absorption between the mains and the consumers' appliances, is of great and important moment.

Especially is this true when it is recognized that gas companies do not wish to increase their street main pressures abnormally for the purpose of overcoming loss of pressure resulting from meter absorption, or otherwise, for obviously, if increase in pressure means a corresponding increase in pressure on all joints throughout the distribution lines, which in turn means an increase in the amount of leakage, which the company suffers, and which is a direct loss, 60 the desire of a gas manufacturer is to distribute the gas under reasonably low pressures. Usually, in large cities, the distribution pressure will run anywhere from 2" to 5" water column per square inch, or an 65 average distribution pressure of 3" to 3 $\frac{1}{2}$ " water column. Under this pressure, it is 70 highly important that the meter or measuring instrument in use should absorb the least possible amount of pressure in operation, 75 thus leaving available the maximum pressure for direct application at the consumers' burners or appliances. This is particularly true in the present day use of gas for industrial purposes and in the household, 80 where gas is used for lighting on Welsbach mantles, or for cook stoves or other appliances, for in such cases, about ninety per cent. of all gas used is consumed through the so-called "Bunsen" burner, in which 85 the gas pressure is depended upon for proper mixture of gas and air for proper combustion, determined by the adjustment of the burner. The natural desire is to distribute gas under the lowest reasonable pressure, and although seemingly paradoxical, 90 nevertheless it is desired, at the same time, to deliver gas at the highest reasonable pressure. Therefore, it is highly important 95 that the meter itself measure and pass the 100 gas with the least possible absorption of pressure.

In the Standard meter, it is figured that an absorption of $\frac{1}{2}$ " water column pressure per square inch for meter operation, is allowed, which is a loss of pressure in operation. Therefore, my purpose is, as above indicated, to increase the capacity of the meter, without increasing its external dimensions, without increasing the pressure 110

absorbed from the meter operation, and without increase in speed ratio of the meter. This I do by increasing the number of valves employed and structurally changing the meter unit to adapt it for coöperation with the additional valves and by certain changes in the mode of operation of the valves, and so constructing the parts that the volumetric capacity of the dia-

5 phragms or measuring chambers for each complete cycle, will greatly increase the amount of gas measured and accordingly increase the capacity of the meter as represented in cubic feet of gas passed per hour,

10 15 without a corresponding increase in the number of cycles or revolutions of the working parts of the meter. This, in effect, is a reduction in the speed ratio of the meter or a reduction in the number of revolutions of 20 the meter per cubic foot of gas measured. By this reduction in the speed ratio per foot, the moving parts of the meter are subjected to less wear in delivering any given quantity of gas and less strain or torque 25 on the moving parts, with consequent great durability and longer life of the meter, and accuracy and reliability in measuring the gas, which accuracy results primarily from the absence of lost motion due to wear.

30 I have found in practice, taking the ordinary thirty light meter as a type, that without increasing its external dimensions, I can, with my improvements, get a greatly increased capacity. The average capacity 35 of the thirty light meter is approximately 600 cubic feet of gas per hour, at approximately 960 revolutions per hour of the working parts, with speed ratio of $1\frac{6}{10}$ revolutions for each cubic foot.

40 I have improved this thirty light size meter so that I can, without in any way changing the external dimensions of the meter, pass approximately 800 cubic feet of gas per hour, at the same time reducing the 45 speed ratio from $1\frac{6}{10}$ revolutions per foot, to $1\frac{4}{10}$ revolutions per foot, and this, without increasing the pressure absorption by the meter in operation.

50 It will be apparent from the foregoing, that the increase in capacity of meter units of any present standard capacity, will cause a decrease in the number of units required for any given purpose, or to meet any given requirement, and that there will be a cor-

55 responding decrease in expense incident to manifolding or connecting up the various units and an incident saving in floor space. For instance, I estimate that with my improvements, the capacity of the meter unit 60 is increased 33 $\frac{1}{3}$ %, consequently where nine meters of former construction are required in a given instance, six of the improved meters would suffice. So far as I am aware, in meters heretofore constructed, the gas 65 enters the meter from the intake through a

gas-tight channel supported upon the valve table. In my improvements, I provide above the valve table, a plate spanning the entire area of the meter, thus forming a gas compartment or chamber above the valve 70 table, entirely separated from the upper part of the meter. I am thus enabled to introduce a greater volume of gas with a consequent increase in pressure, and I also slightly increase the size of the intake and 75 outlet openings to meet this changed condition.

With the above and other objects, having in view the structural improvements of meters in detail, which will become apparent 80 in the course of the following description, the invention consists in the novel combination and arrangement of parts whereby my objects are accomplished.

In the drawings illustrating the invention; 85

Figure 1 is a top plan view of the meter embodying my improvements, with the top removed and a plate immediately below it, partly broken away to show the valve ar- 90

range ment.

Fig. 2 is a horizontal section of the meter taken below the valve table and looking toward the top of the meter.

Fig. 3 is a section taken about on line $a-b$ 95

Fig. 1.

Fig. 4 is a transverse section of portions of the meter below the valve table, taken about on line $c-d$ of Fig. 2.

Fig. 5 is a detail elevation of the valve 100 operating shaft, showing the manner of connecting the valve arms to the cranks of the shaft.

Fig. 6 is a top plan view of Fig. 5.

Fig. 7 is a cross section of one of the 105 valves, valve seat, and a portion of the valve table and channels below the same.

Referring to the drawings, the numeral 1 designates the casing, which in exterior formation does not differ in any material way 110 from the casing now commonly used, which is rectangular in shape and comprises front and rear walls 2 and 3, side walls 4 and 5, and top 6, and intake and outlet manifolds A and B, respectively, and of course, a suitable bottom, not shown. The numerals 7 and 8 designate diaphragms of the bellows type, and of usual construction, that is to say, comprising circular metallic plates 9 and 10, which are connected to a central metallic ring 11 by leather sections 12, which adapt the diaphragms for the usual dilating and contracting movements caused by the flow of gas into and out of them, during the movement of the meter parts. The diaphragms are suitably supported centrally, and the plates 9 and 10, may be connected in the usual way to the flags of the meter.

These diaphragms, while they operate in unison to receive and expel the gas are in- 130

dependent of, or separated from each other by a vertical central partition 13 to which the diaphragms are attached. The partition extends from the bottom of the meter to 5 the valve table, which is designated by the numeral 14, the partition extending also to the sides of the meter casing, thus forming two diaphragm chambers in which the gas, in passing through the meter, flows, and 10 whose pressure in the chambers is utilized under certain valve controlled operations, to exert a pressure upon the diaphragms to cause their collapse and the consequent ejection of gas therefrom, through suitable ports 15 and channels to the outlet or discharge opening of the meter.

The numerals 15 and 16 designate the flagstaffs stepped in suitable bearings at the bottom of the meter, and extending upwardly through the stuffing boxes 17 and 20 18, rigidly supported in the present instance, by the valve table and flange of an additional plate, which I provide in the upper portion of the meter, and which will be presently described in detail. The stuffing box in the present instance is, for the purposes of strength, made somewhat longer than the usual stuffing box, so that it may span the space between, and have the support of the 25 valve table 14, and the additional plate just mentioned.

Each of these staffs carries the usual flag 30 18' secured to the shaft or otherwise rigidly connected therewith, and having swivel connection with the outer metallic plates of the diaphragms, as indicated at 19, so that the expansion and collapsing of the diaphragms, caused by the flow of the gas through the diaphragms and meter casing, will cause oscillation of the flagstaffs and consequently 35 through certain link and arm connections about to be described, operate the valves, which, in turn, control the admission of gas into and out of the diaphragms and into, 40 and out of the casing, and out of the channels which communicate with the outlet opening.

Mounted at the upper end of the staff 15 is staff arm 20 and upon the upper end of the 50 staff 16 is mounted staff arm 21, and to the free end of the arm 20, is pivotally connected link 22 and to the corresponding end of arm 21, link 23 is similarly connected, and both of these links are pivotally connected 55 with a stud 24, carried by the threaded adjusting nut 25, working on the threaded tangent 26, which in turn is rigidly connected to the upper end of the valve operating shaft which shaft is stepped at its lower end 60 into a socket in a stud 28, approximately centrally located upon the valve table 14, which forms the lower bearing for the shaft. A further bearing for the valve operating shaft is formed on the upper side of a substantial metallic disk 29, and is constituted

by a stuffing box 30 through which the shaft above the cranks extends. This disk is supported on the valve table by a plurality of posts 31, sufficient in number to provide the required rigidity of the disk to adapt it to 70 serve as bearings for other operating parts.

Mounted upon this disk is an ear 32 which serves as a bearing for the horizontal dial shaft 33, which shaft carries a worm gear 34 in mesh with worm 35, secured to the valve 75 operating shaft, and through which the revolutions of the valve operating shaft are communicated to the dial shaft and accordingly to the mechanism at the front of the meter, which mechanism at the front of the 80 meter, which mechanism and manner of operating the same in the present instance, is like that commonly employed for this purpose and consequently no further detail description of this mechanism is necessary.

The numeral 36 designates, as a whole, an 85 additional plate peculiar to my construction, which plate spans the entire interior area of the upper part of the meter and is sufficiently spaced from the valve table to allow for introduction and operation of the valves 90 and their connected parts, and with the valve table and the walls of the meter casing, forms a tight gas chamber 36', into which the gas, through the meter inlet, enters before passing into any other parts of the 95 meter. This plate 36 also forms, with the top and sides of the casing, a separate gas-free chamber 36'', which gives free access for adjustment of the meter at the time of 100 test or proving. This plate 36 is of separable character, that is to say, when complete, it comprises an edge flange 37 soldered or otherwise attached in a gas-tight manner, to the walls of the meter, and this rectangular flange extends outwardly for a short distance, leaving a large rectangular opening 105 38 through which access can be had to the valves, and their connected parts, for the purpose of installation, in the first instance, or for the purposes of repair thereafter. In the 110 completed structure, this aperture is entirely covered by a rectangular plate 39, flanged downwardly at its edges to fit over corresponding upturned edge-flanges 40 of the large flange 37, to which flanges 40, the plate 115 is soldered. This plate 39 is further soldered to the disk 29, and thus a very rigid and durable construction is produced.

Reverting to the valve operating shaft, I provide this shaft with three cranks 41, 42 120 and 43, instead of with one crank, which characterizes meters of usual construction. Connected to the crank 41 by valve arm 44, is a valve 45, and connected with the crank 43, by valve arm 46, is valve 47. To the intermediate crank 42, through valve arms 48 and 49, are connected valves 50 and 51, the connections between the cranks and the valves, as shown, being pivotal connections, as usual. The valves 50 and 51 are, as I have 130

termed them, primary valves, and valves 45 and 47 are supplementary valves, and the angulation of the cranks is such that a primary valve and a supplemental valve, located on one side of the partition, work in unison, and a primary valve and supplemental valve on the other side of the partition, also work in unison. All of the valves are provided with guide rods 52 which work 10 through apertures in studs 53 supported on the valve table, thus insuring accurate lineal movement in the reciprocation of the valves.

The numerals 54, 55, 56 and 57, designate the valve seats which are rectangular in 15 shape and suitably supported in the valve table, and extend a short distance above the same, as clearly shown in Fig. 3. Each seat is provided with three ports, one leading to the diaphragm, another to the casing, or to 20 the gas-tight chamber, in which the diaphragm is located, and the remaining or central port leading to the outlet or discharge channel which, as will appear presently, communicates with the outlet or discharge 25 opening of the meter. For the purpose of strengthening the seats, a central rib is cast integral with them, which rib stops short of the upper or bearing edges of the valves, and seemingly gives to each valve, six ports, but 30 since any two ports in a valve seat divided by the rib, will establish gas communication with either the diaphragm, diaphragm casing and outlet channel simultaneously, they can, and will be for the purpose of this 35 description, regarded as single ports. The numeral 58 designates the inner or diaphragm ports, 59 the casing ports, and 60 the outlet ports, that is to say, the ports that establish 40 communication between the chamber 36' and the diaphragms, and between the diaphragms and the outlet ports, and from the chamber 36' to the casing, and from the casing to the outlet ports, through the various 45 channels provided for the transfer of gas from one point to the other.

The numerals 61 and 62 designate the two diaphragm channels, that is to say, the breathing channels or the channels through 50 which the diaphragms successively fill and empty. These, as shown clearly in Fig. 4, are located one on each side of the central partition 13. The channel 62 opens at its upper end into channel 63, leading to the ports 58 in valve seats 56 and 57 which are 55 successively covered and uncovered in the movement of the valves to seal the diaphragm ports against flow of gas to the diaphragms, and to permit the gas to pass from the channel 63, through the diaphragm 60 ports 58, through the valve and through the ports 60, in valve seats 56 and 57, to the outlet channel 64, and to the meter outlet "B". The channel 61 opens at its upper end into channel 65, similar in all respects to 65 channel 63, on the opposite side of the par-

tition 13, and the channel 65, in turn communicates with the diaphragm ports 58, through the valves, through the outlet ports 60, in the other valve seats 54 and 55, to the outlet channel 66, which also leads to 70 the outlet B. In other positions of the valves (the valves and valve seats being of identical construction), than that shown in Fig. 7, they will close the casing ports 59 against the flow of gas into the casing from 75 chamber 36' and establish communication between the casing and the outlet ports 60. The operation of the valves is successive, say, first to permit the gas to flow through 80 the diaphragm ports 58, through the channels into the diaphragms and out of the diaphragms to the outlet and from the casing to the outlet.

The numeral 67 designates an arm having a downwardly extending angular portion 85 soldered or otherwise attached to the disk 29. This arm is provided at its inner end with an eye which surrounds the upper part of the valve operating shaft, and serves as a bearing for the same. Pivoted in a slot 90 in the outer end of this arm, is a pawl 68, provided below its pivotal point with a shoulder adapted to limit its movement in one direction. This pawl is engaged by the tangent in the revolution of the meter parts, 95 the movement of the tangent being unobstructed in one direction, but entirely prevented in the other direction, thus providing against retrograde movement of the parts, all of which is usual in meters of this 100 character.

The numeral 69 designates a baffle which I place between the valve table 14 and the plate 36, opposite the intake opening. This baffle, as shown in dotted lines in Fig. 1, 105 extends only a short distance across the meter and serves the purpose of preventing the introduction of an instrument through the intake opening, to tamper with the mechanism.

In operation, gas comes in through the intake manifold A, into the chamber 36', and in the position of the valves shown in Fig. 1, which we may take as a starting point, the gas flows through the ports 58 115 which are open, to one of the diaphragms and as soon as the gas begins to flow into a diaphragm, the movement of the parts is started, which starts the opening of diaphragm ports 58 on the other side of the partition, and during this part of the cycle of the mechanism, both diaphragms are being filled. A further movement will move the valves to close the diaphragm ports against gas from chamber 36', and establish 120 communication between said ports through ports 60, to outlet channels, and opening the casing ports 59, permitting gas to flow into the casing to collapse the diaphragms and force the gas out of them.

When the diaphragms are emptying at their full capacity, the position of the valves will be such as that shown in Fig. 7. Then the valve has reached the limit of its forward movement and will continue the emptying until the front flange of the valve in its rearward movement has completely closed the port 58 and at this time, the rear flange of the valve has closed the casing port, preventing intake to the casing from the chamber 36'. Its continued rearward movement opens the diaphragm port 58 for the intake of gas from the chamber 36' and immediately establishes communication for the outlet of gas from the casing, through the port 59, through the valve to the outlet port 60, through which it passes to the main outlet.

It will be noted that the connections between the flagstaffs, tangent and valve operating shaft, are above the plate 36, and between said plate and the cover proper of the meter, thus providing a gas-free chamber above the plate, and giving ready and convenient access to the adjustment mechanism, without the necessity of emptying the meter.

Having thus fully described my invention, what I claim is:—

- 30 1. In a gas meter, a casing having compartments therein, in combination with the inlet and outlet, two diaphragms located in separate compartments, four valves controlling the flow of gas into and out of the diaphragms and their compartments, mechanisms for operating the valves, and suitable channels for conducting the gas to the meter outlet after it has passed through the diaphragms and their compartments.
- 40 2. In a gas meter, in combination, a casing having compartments therein, two diaphragms in separate compartments, four valves, two of which control the service of gas to and from one diaphragm and its compartment and the other two valves controlling the service of gas to and from the other diaphragm and its compartment, a single valve operating shaft, and connections between the shaft and all of the valves.
- 50 3. In a gas meter, in combination, a casing having compartments therein, two diaphragms located in separate compartments, four valves, two of which control the service of gas to and from one diaphragm and its compartment, and the other two valves controlling the service of gas to and from the other diaphragm and its compartment, a single valve operating shaft formed with three cranks, connections between two of the cranks and two valves respectively, and connections between the other two valves and the remaining crank.
- 60 4. In a gas meter, in combination, a suitable casing having compartments therein, two diaphragms, a pair of valves control-
- 65 ling the flow of gas to and from one diaphragm and its compartment, and two valves controlling the flow of gas to and from the other diaphragm and its compartment, a single valve operating shaft and connections between the valves and operating shaft, whereby two valves in each pair will operate in unison.
- 70 5. In a gas meter, in combination, a suitable casing having compartments therein, two diaphragms in separate compartments in the casing, a pair of valves for each diaphragm and its compartment, a single valve operating shaft formed with three cranks, connections between two of the cranks and two valves respectively, and connections between the other two valves and the remaining crank.
- 75 6. In a gas meter, in combination, a suitable casing, a valve table, a gas tight chamber above the table and formed by a plate intermediate between the valve table and the top of the meter casing, and completely spanning the space above the table, a meter inlet communicating with the chamber, and a suitable meter outlet.
- 80 7. In a gas meter, in combination with a plurality of separate gas-tight chambers of diaphragms located in said chambers, and the meter intake and outlet, of a primary set of valves and a supplemental set, one valve of the supplemental set working with a valve of the primary set to serve one diaphragm and chamber, and a valve of the primary set working with a valve of the supplemental set to serve the other diaphragm and the chamber in which it is located, a valve operating shaft, means for operating said valves to establish communication between the meter inlet and outlet openings through the diaphragms and the chambers in which the diaphragms are located.
- 85 8. In a gas meter, in combination with a plurality of separate gas-tight chambers of diaphragms located in said chambers, and the meter intake and outlet, of a set of primary valves, and a supplemental set, a valve of the supplemental set working in unison with a valve of the primary set to serve one diaphragm, and another valve of the primary set working in unison with another valve of the supplemental set to serve the other diaphragm, and the chamber in which it is located, a valve operating shaft, means for operating said valves to establish communication between the meter inlet and outlet openings, through the diaphragms and the chambers in which the diaphragms are located.
- 90 9. In a gas meter, in combination, a suitable casing, a plurality of diaphragms and the meter intake and outlet, of a valve table above the diaphragms, a partition arranged within the meter casing and forming with the walls of the meter, and the valve table,
- 100 105 110 115 120 125

- separate chambers for the diaphragms, a primary set of valves and a supplemental set, a valve of the supplemental set working with a valve of the primary set on one side 5 of the partition, and a valve of the primary set working with a valve of the supplemental set on the other side of the partition, a valve operating shaft having connections with the valves, valve seats having suitable 10 ports adapted to be covered and uncovered by the valves in their movement to establish communication between the meter inlet and outlet openings, through the diaphragms and meter casing.
- 15 10. In a gas meter, in combination, a suitable casing, a plurality of diaphragms and the meter intake and outlet, of a valve table above the diaphragms, a partition arranged within the meter casing and forming, with 20 the walls of the meter and the valve table, separate chambers for the diaphragms, a primary set of valves and a supplemental set, a valve of the supplemental set working in unison with a valve of the primary set 25 on one side of the partition, and a valve of the primary set working in unison with a valve of the supplemental set on the other side of the partition, a valve operating shaft having connections with the valves, suitable 30 ports adapted to be covered and uncovered by the valves in their movement to establish communication between the meter inlet and outlet openings, through the diaphragms and meter casing.
- 35 11. In a gas meter, in combination, a suitable casing, a plurality of diaphragms and the meter intake and outlet, of a valve table above the diaphragms, a partition forming with the valve table and the meter casing, 40 separate diaphragm compartments, separated valve seats on each side of the partition, and provided with ports, a primary set of valves and a supplemental set, a valve of the supplemental set working in unison with 45 a valve of the primary set on one side of the partition, and a valve of the primary set working in unison with a valve of the supplemental set on the other side of the partition, a valve operating shaft and connections 50 between the shaft and the valves whereby, when the valves are operated the ports will be covered and uncovered to establish communication between the meter inlet and outlet openings through the diaphragms and the diaphragm compartments.
- 55 12. In a gas meter, in combination, a suitable casing having compartments therein, and an intake and outlet, two diaphragms located in separate gas-tight compartments, a 60 valve table above the diaphragms, valves on said table, two for each diaphragm, an operating shaft, connections between the operating shaft and the valves, whereby the valves in each set are operated in unison 65 to serve one diaphragm and its compartment.

ment, suitable valve seats having ports in the valve table communicating with the diaphragms and with the compartments in which they are located; and with suitable outlet openings, whereby communication is 70 established between the intake and outlet openings.

13. In a gas meter, the combination with a suitable casing having compartments therein and an inlet and outlet, two diaphragms 75 located in separate compartments, a valve table above the diaphragms and having ports therein communicating with the diaphragms, and their compartments, suitable outlet channels communicating with said 80 ports, a valve operating shaft formed with three cranks, valves adapted to be reciprocated to open and close the ports, two of the valves being connected with one of the cranks and two of the valves connected one 85 each with the other two cranks.

14. In a gas meter, in combination with a suitable casing having compartments therein and an inlet and outlet, two diaphragms located in separate compartments, a valve 90 table having ports therein for serving the diaphragms and their compartments separately, valves adapted to cover and uncover said ports, an operating shaft having connection with the valves, whereby when the 95 shaft is rotated, the valves are reciprocated, and a plate in the meter casing above the valve table and intermediate between said table and the top of the casing, and spanning substantially the entire space between the 100 casing walls, thus forming, with the valve table, a gas chamber for the reception of the incoming gas and from which chamber the gas is supplied below the valve table.

15. In a gas meter, the combination with a 105 suitable gas-tight casing, a diaphragm in said casing, a suitable intake and an outlet, a valve table, valves on said table for controlling the flow of gas to the lower part of the casing, and mechanism through which the 110 valves are operated, and a plate above the valve table and intermediate between said table and the top of the casing which, with the casing, forms a gas chamber for the reception of the gas, said chamber having communication with the intake opening of the 115 meter.

16. In a gas meter, in combination with a suitable casing having compartments therein, and an intake and outlet, of two diaphragms located in separate compartments, a valve table above the diaphragms and having separated diaphragm, outlet, and casing ports therein, a plurality of valves for each diaphragm and its compartment, a channel 120 leading from one diaphragm to the diaphragm ports of two valves, and a channel in common with the outlet ports of two valves, and a channel communicating with the other diaphragm and with the dia- 125 phragm ports of two valves, and a channel in common with the outlet ports of two valves, and a channel communicating with the other diaphragm and with the dia- 130

phragm ports of the other two valves, and a channel to the outlet ports of the last mentioned two valves, the outlet channels communicating with the meter outlet.

5 17. In a gas meter, in combination, a suitable casing having intake and outlet openings, a plurality of channels for directing the flow of gas from the intake to the outlet, through the casing, said outlet channels being formed with bottoms inclining generally downward from the inlet toward the outlet, substantially as and for the purpose set forth.

10 18. In a gas meter, in combination, a casing having intake and outlet openings, a valve table, a plurality of channels below the table for directing the flow of gas through the casing, said outlet channels being formed with bottoms inclining generally downward from the intake toward the outlet.

15 19. In a gas meter, in combination, a casing having intake and outlet openings, a valve table, a plurality of channels secured to the under side of the table for directing the course of gas through the casing, said outlet channels being formed with bottoms inclining generally downward from the intake toward the outlet.

20 20. In a gas meter, in combination, a suitable casing, a valve table, valves on said table, a crank shaft, and connections between the valves and shaft, whereby the valves are reciprocated, a plate rigidly supported above the valve table, and spaced therefrom, said plate serving as a bearing for the valve operating shaft, and means for supporting the plate.

21. In a gas meter, in combination, a suitable casing, a valve table, a valve operating shaft, valves on the table having connection 40 with the operating shaft, for the purpose set forth, and a plate above the valve table and spaced therefrom, a plurality of posts mounted on the valve table, and supporting said plate and a stuffing box for the operating shaft carried by the plate. 45

22. In a gas meter, in combination, a suitable casing, a valve table in the casing, valves on said table, a valve operating shaft, connections between the shaft and the valves, 50 whereby the valves are operated, a circular plate above the valve table spaced therefrom, posts carried by the valve table and a stuffing box for the operating shaft, carried by the plate, the plate serving also as a support 55 for other operative meter parts.

23. In a gas meter, in combination, four valves, an operating shaft having three cranks, and suitable connections between the cranks and the valves, whereby the valves 60 are operated.

24. In a gas meter, in combination, four valves, an operating shaft having three cranks, connections between two of the cranks, and two valves respectively, and connections between the other two valves and the remaining crank, whereby the valves are 65 operated.

In testimony whereof I affix my signature in presence of two witnesses.

EDMUND S. DICKEY.
